UNITED STATES PATENT OFFICE.

MARCELINO CARRANZA, OF BUENOS AIRES, ARGENTINA.

CARPET-MANUFACTURING MACHINE.

Application filed July 17, 1924. Serial No. 726,607.

To all whom it may concern:

Be it known that I, MARCELINO CARRANZA, a citizen of the Republic of Argentina, residing at 1051 Viamonte Street, Buenos Aires, Argentina, have invented certain new and useful Improvements in Carpet-Manufacturing Machines, of which the following is a specification.

The present invention relates to an improved machine adapted to be used in the manufacture of carpets, its object being to provide a very simple and economical machine which will reduce the cost of producing carpets to a low figure. This machine is adapted to produce a kind of tufted cord or chenille which is thereafter used as the weft to produce a chenille carpet in any suitable loom. The machine according to the present invention consists of a rotary parallel lathe which is adapted to produce the cord in any length or size depending upon the size of the bars used, which bars form one of the objects of the invention. A further object of this invention is to produce a tufted cord which consists in winding the wool threads around two suitably spaced cords, sewing the threads to the cords and then cutting the threads on a line intermediate the cords to thus produce a tufted cord of twice the length of the bars on which it is produced. Another object consists in constructing a lathe which is adapted to receive a cord by means of a pair of bars and around said cord and bars a thread is wound which forms the tread of the carpet.

Other objects will be apparent from the following description taken in connection with the accompanying drawings in which corresponding numerals indicate like parts throughout and in which:

Figure 1 is a front view of the complete lathe showing parts in section,

Fig. 2 is a sectional view thereof on line A—B of Fig. 1.

Fig. 3 is a plan view of the lathe,

Fig. 4 shows an end view, a section, and a front view of the circular disk, and

Fig. 5 is a front view of the secondary disk.

The lathe of this invention consists of a metal base member 1 having secured thereto at each end a head piece 3 by means of bolts 4 and 5. Each head piece has a rotatable shaft 6 secured therein, the shaft in the left head piece being secured in place by means

of nuts 8 and 9. The shaft in the head piece at the right indicated by 13 in Fig. 1 is the driving shaft and is longitudinally movable in its head piece. This right shaft 60 is secured in place and is adjustable by means of a driving pulley 37 screw-threaded on the shaft. This driving shaft also is provided with a pinion 11 having a key 34 which is adapted to engage and slide in slot 65 35 in the shaft. Thus the pinion will allow the driving shaft to be adjusted longitudinally but will rotate therewith. The inner ends of the shafts 6 are provided with forks 7 each having suitable openings therein for 70 the reception of the retaining pins 14. As will be seen from the drawing each shaft 6 is provided with a ball bearing 10 which act as thrust bearings for the head pieces since certain parts, as will be explained, are tensioned between the forks and the bearings will thus reduce the friction to a minimum. 75

The forks 7 of the shafts 6 are adapted to receive, by means of the pins, a pair of separable bars 15 of iron or any other suitable material. These bars may be of varying sizes including length, breadth and thickness, depending upon the thickness and size of the carpet to be manufactured.

Each head piece forms a bearing for a 85 threaded rod 20 having a thrust bearing 24 at each end and rotatably secured in the head pieces by means of nuts 25, 26 and 28, the latter of which is threaded on the end 90 27. This rod is supported at intervals, depending upon its length, by a bearing 23 which supports the rod at the reduced portion 21. This bearing has a semicircular cross-section as will be seen from Fig. 2 and is furthermore provided with a chamber 29 into which oil is introduced through a suitable hole 31 in the side 30. This bearing is suitably secured on the base member 1 as shown and its upper ends in which the bearing surface is provided terminates in a 100 plane intersecting the axis of the rod 20 so that the bearing surface in cross-section is in the form of a semicircle in order that the steel guide block 40, which also has a bearing surface having a cross-section somewhat smaller than a semicircle, may pass thereover as is clearly illustrated in Fig. 2 of the drawing.

The mechanism which guides the wool 110 42, which forms the tufts of the chenille, comprises the steel guide block 40 which is screw-threaded and is in the form of a semi-

cylinder. This guide is supported off and is adapted to travel on the rod 20 by means of the corresponding screw-threads and it further comprises a vertical plate 45 which 5 is soldered or otherwise suitably secured thereto. This plate has a weight 46 fixed near its lower end in order to suitably balance the guide on the rod 20. A supporting arm 43 is secured on the side of the 10 guide opposite to that on which the plate is secured and terminates in a guide ring 44 which is adapted to partially surround the bars 15 as shown in Fig. 2. This guide ring 44 is adapted to suitably guide the 15 circular retaining member 50 as will be explained. An electric switch box 47 is secured to the plate 45 and is provided with a switch handle 48, the current entering the box by means of wire 49. This handle as 20 will be seen is within easy reach of the operator and thus the machine, which is adapted to be operated by an electric motor by means of pulley 37 can be easily and readily controlled. The opening of the 25 electric circuit may also be automatically effected by any other suitable means, as for instance by means of the guide 40 striking a switch at the end of its travel. Instead of the weight 46 a bar may be fixed to the plate 30 45, said bar, not shown on the drawing, carrying a suitable number of bobbins for the wool thread, each of which being then provided with the usual tensioning means. In this manner a very regular and automatic 35 operation may be obtained. A guide pin 41 is secured on the guide 40 for guiding the wool thread 42.

The main retaining member or disc 50 40 consists of a disc of fibre or metal as shown in Fig. 4 and is provided with a slot 59 corresponding to the thickness of the bars 15 and whose length is equal to the width of both bars as placed in the machine together with the thickness of the cord 17. The 45 purpose of the retaining disk is to hold both bars 15 securely in place during rotation in order to prevent them from stretching apart due to centrifugal force when the lathe is turning at a speed of 1000 revolutions per 50 minute or more. A further purpose of this disk is to hold the bars firmly in place immediately before the bars are wound with the wool thread 42, this disk being adapted to travel with the guide, since it is moved forward by the ring 44 due to the movement 55 of the guide 40. Secondary guide plates 53 are also used which are suitably placed at suitable intervals on the bars 15 for holding them together and these plates are moved along with the disk 50 during operation when the guide 40 reaches them.

In order to compensate for the tightness and strains caused by the rod 20 and the bars 15, ribs 32 and 33 are provided in each 60 of the head pieces, which bear against the

base 1 and thus prevent any tendency of the head pieces 3 from being bent inwardly or broken off. The head piece 3 which supports the pulley 37 by means of the shaft 6 is provided with a recess 38 in which any suitable iron bar, not shown, may be inserted in order to secure the shaft 6 from turning due to its contact with a flat side of the fork 7 by merely forcing the bar manually against the flat side. This is necessary in order to tighten the bars 15 in the forks by means of the pulley 37. 70 75

The operation of the machine is as follows:

The pulley is given three or four revolutions in the reverse direction preventing, at the same time, the shaft 6 upon which the pulley is mounted from rotating in order to loosen the shafts 6. With the bars 15 in place in the left fork 7 by means of the pins 14 passed through holes 16 in the bars, the cord 18 is passed around the outside edges of the bars from the spool 54, as indicated on the drawing by means of the numeral 17, and then the necessary number of secondary guide plates 53 are placed on the bars including also the disc 50, which is, of course, first placed on the bars and against the ring 44. This assembly is now placed in the right fork and secured in place by the pins 14 after which the cord 18 is tied at the right end of the bars and the ends cut off, as indicated at 19. After setting an iron bar into the recess 38 to avoid the turning of the right shaft 6, the pulley 37 is tightened against the pinion 11 which thus will tension the bars in the forks. By any suitable operation the guide 40 is placed to the extreme left of the machine and the guide plates are then suitably spaced on the bars. The wool thread is now set in place by forcing its end between the side of the fork and the bar or between the rod and the cord at the point 55 and it passes over the guide 40 and is retained by the guide pin 41. The machine is then started and motion is imparted to the pulley 37 by any suitable transmission belt which in turn rotates the bars and the pinion 11. This pinion will impart motion to the pinion 12 by any suitable chain transmission, not shown, which will thus impart motion to the rod 20. At a speed of approximately 1000 revolutions per minute the guide 40 will travel from the left to the right due to the screw-threads in the direction of the arrow 52 and thus wind the wool thread on the cord and the bars. After the winding operation the bars with the thread and cord thereon are taken out of the machine by loosening the bars and removing the pins and the wool threads are then sewed to the cord on any suitable sewing machine, not shown. Fig. 1 shows by the short dotted lines at the left on the 100 105 110 115 120 125 130

cord 17 and the cross-threads the line of stitches and line 56 indicates where the novel threads are cut after the sewing operation is completed. It is to be remembered that the sewing operation is carried out while the threads and cord are still on the bars and both sides may be sewed on a double sewing machine or each side may be sewed separately depending upon the type 10 of sewing machine used. After the wool threads are cut the bars are easily removed and thus a tufted cord is produced in two lengths, each being as long as the bar. It is thus apparent that the finished chenille 15 may be of any desired size and thickness depending upon the size of the bars used. This tufted cord is now used as the weft in any suitable loom to produce a carpet by any suitable weaving operation. The operation 20 described in the foregoing is set forth by way of example but it is to be understood that the steps may be interchanged, depending upon the skill of the operator or the speed at which the finished cord is to be 25 produced.

It is obvious that many constructional and other changes may be introduced without departing from the scope of the present invention.

30 I claim as my invention.

1. A tufted cord making machine comprising a base member; a pair of separable bars rotatably mounted on said base, said bars being adapted to receive a cord around 35 the edge thereof; and means for rotating said bars in order to wind a thread around said bars and the cord.

2. A tufted cord making machine comprising a base member; a pair of head pieces 40 mounted on said base member; a shaft mounted in each head piece, each of said shafts having a fork at its inner end; a pair of bars removably mounted in said forks and adapted to receive a cord; a screw-threaded rod rotatably mounted in said head pieces; a guide mounted on said rod and adapted to be moved on and by the screw-threads of said rod, said guide being 45 adapted to convey and guide a thread; and means for rotating said shafts and rod in order to wind said thread around said cord.

3. A tufted cord making machine comprising a base member; a pair of head pieces mounted on said base member; a shaft 50 mounted in each head piece, each of said shafts having a fork at its inner end and one of said shafts being longitudinally adjustable; a pair of bars removably mounted in said forks and adapted to receive a cord and be tensioned by means of 55 said longitudinally adjustable shaft; a screw-threaded rod rotatably mounted in said head pieces; a guide mounted on said rod and adapted to be moved on and by the screw-threads of said rod, said guide 60

being adapted to convey and guide a thread; and means for rotating said shafts and rod in order to wind said thread around said cord.

4. A tufted cord making machine comprising a base member; a pair of head pieces mounted on said base member; a shaft mounted in each head piece, each of said shafts having a fork at its inner end and one of said shafts being longitudinally adjustable; a pair of bars removably mounted in said forks and adapted to receive a cord and be tensioned in said forks by means of the longitudinally adjustable shaft; a pulley screw-threaded on the other end of said 70 shaft longitudinally adjustable shaft adapted to drive said shafts and to form a locking means for said adjustable shaft; a screw-threaded rod rotatably mounted in said head pieces and adapted to be rotated in said 75 adjustable shaft; and a guide mounted on said rod and adapted to be moved along by the screw threads, said guide being adapted to convey and guide a thread in order to wind the thread around said cord. 80

5. A tufted cord making machine comprising a base member; a pair of head pieces mounted on said base member; a shaft mounted in each head piece, each of said shafts having a fork at its inner end; a pair 85 of bars removably mounted in said forks and adapted to receive a cord; a screw-threaded rod rotatably mounted in said head pieces and adapted to be rotated by one of said shafts; a guide mounted on said rod 90 and adapted to be moved along by the screw threads, said guides being adapted to convey and guide a thread; and means for rotating said shafts in order to wind said 100 thread around said cord. 105

6. A tufted cord making machine comprising a base; a head piece mounted at each end of said base, said pieces comprising bearing supports; a shaft having a forked end in each head piece; a rod mounted in 110 said head piece; a guide mounted on said rod and adapted to be controlled by the rotation of said rod; a pair of bars adapted to be inserted in the forked ends of said shafts and to receive a cord; and means for 115 rotating said bars and moving said guide so that said guide may direct a thread around said bars and cord.

7. A tufted cord making machine comprising a base member; a pair of head pieces mounted on said base; a shaft having a forked end in each head piece; a rod mounted in the head pieces; a thread guide mounted on said rod; a pair of bars adapted to be removably inserted in said 120 forked ends of said shafts and to receive a cord; and means for rotating said bars and moving said guide so that said guide may direct a thread around said bars and cord. 125

8. A tufted cord making machine com- 130

- prising a base member; a pair of head pieces mounted on said base; a shaft for each head piece; a rod mounted in said head pieces; a guide for a thread mounted on said rod and adjusted to be controlled thereby; a pair of bars adapted to be inserted in said shafts and to receive a cord; and means for rotating said bars and moving said guide so that said guide may direct the thread around said bars and cord.
9. A tufted cord making machine comprising a base member; a pair of head pieces mounted on said base; a shaft for each head piece; a rod mounted in said head pieces; a guide for a thread mounted on said rod and adjusted to be controlled thereby; a pair of bars adapted to be inserted in said shafts and to receive a cord; means for rotating said bars and moving said guide so that said guide may direct the thread around said bars and cord; and a plurality of discs on said bars in order to prevent the bars from spreading due to centrifugal force.
10. A tufted cord making machine comprising a base member; a pair of bars rotatably mounted on said base, said bars being adapted to receive a cord; means for rotating said bars; means for winding a thread around said bars and the cord while said bars are rotating; and a plurality of discs on said bars in order to prevent the bars from spreading due to centrifugal force.
11. A tufted cord making machine comprising a base member; a pair of shafts mounted to rotate on said base member; a rod rotatably mounted on said base member; a guide for a thread mounted on and controlled by said rod; a pair of bars adapted to be inserted between said shafts and to receive a cord; and means for rotating said shafts and rod in order that said guide shall direct the thread around said cord and bars.
12. A tufted cord making machine comprising a base member; a pair of shafts mounted to rotate on said base member; a rod rotatably mounted on said base member; a guide for a thread mounted on and controlled by said rod; a pair of bars adapted to be inserted between said shafts and to receive a cord; means for rotating said shafts and rod in order that said guide shall direct the thread around said cord and bars; and a plurality of discs on said bars in order to prevent said bars from spreading, due to centrifugal force.
13. A tufted cord making machine comprising a base member; a pair of shafts rotatably mounted on said base; a rod rotatably mounted on said base member; a guide for a thread mounted and controlled by said rod; a pair of bars adapted to be removably inserted between said shafts and to receive a cord around the outside edges of said bars; and means for rotating said shafts, bars, and rod in order that said guide shall direct the thread spirally around said cord and bars.

In testimony whereof I affix my signature.
MARCELINO CARRANZA.
